UNITED STATES PATENT OFFICE.

HATTIE H. SELL, OF GILBERTSVILLE, PENNSYLVANIA.

CLOTHES-PIN.

1,141,728

Specification of Letters Patent.

Patented June 1, 1915.

Application filed March 26, 1914. Serial No. 827,420.

To all whom it may concern:

Be it known that I, HATTIE H. SELL, a citizen of the United States, residing at Gilbertsville, in the county of Montgomery, 5 State of Pennsylvania, have invented certain new and useful Improvements in Clothes-Pins; and I do hereby declare the following to be a full, clear, and exact description of the invention, such as will enable others skilled in the art to which it 10 pertains to make and use the same.

This invention relates to clothes pins.

The object of the invention is to provide a device of this character adapted to be constructed of a single strand of wire, and which is simple and durable, and will serve to retain an article upon a clothes line against accidental displacement.

With the above and other objects in view 20 the invention consists in the details of construction and in the arrangement and combination of parts to be hereinafter more fully described and particularly pointed out in the appended claim.

25 In describing the invention in detail reference will be had to the accompanying drawings wherein like characters of reference denote corresponding parts in the several views, and in which—

30 Figure 1 is a side elevation illustrating the application of the improved clothes pin; Fig. 2, a perspective view of the clothes pin detached; Fig. 3, a section on the line 3—3 of Fig. 1 showing the keeper at the central 35 portion of the pin before same is moved into confining relation to a clothes line, and Fig. 4, a view similar to Fig. 3 showing the position of the keeper after same has been moved into confining relation to a clothes line.

40 Referring to the drawings the improved clothes pin is indicated generally at A and is shown constructed of a single length of resilient wire bent to form a plurality of coils 10, the outermost coils 10 being connected 45 by one extreme end of the wire 11. The other extreme end of the wire is bent U-shaped as at 12 and the free terminal thereof is adapted to be engaged over the coil 10 remote from the inner end of said U-shaped

end to confine a clothes line 13 between same 50 and the end 11. It will of course be noted that the free terminal of the end 12 can be disengaged from the coil 10 to permit the insertion of the clothes line 13 as clearly shown in the drawings. The wire constituting the 55 pin is further bent and shaped to form on each side of the coils 10 coöperating V-shaped clamping arms 14 and 15, the connected end of these arms being further bent to form loops 16 disposed in planes at right 60 angles to the central plane of the pin. The arms 14 and 15 are provided adjacent the loop 16 with outwardly and inwardly bent portions which form a seat for the clothes line 13 when the pin is applied as will be 65 obvious.

The clothes pin is adapted to be secured to the clothes line 13 by first confining the latter between the ends 11 and 12 in the manner heretofore stated. The arms 15 and 70 16 are then pressed into embracing relation to the clothes line until the latter seats between the outwardly and inwardly curved portions 17. To disengage the pin from the clothes line it is only necessary to draw the 75 loops 16 toward each other.

What is claimed is:—

A clothes pin formed from a single strand of resilient wire bent to form a plurality of coils and two pairs of coöperating clamping 80 arms, the arms of one pair extending from the outer members of the coils and the arms of the other pair extending from the inner members of the coils, the connected portions of said clamping arms being bent to form 85 loops disposed in planes at right angles to the central plane of the pin, and one end of the wire connecting the outermost coils and the other end of the wire being secured to one of the outer coils and bent U-shaped and 90 having its terminal adapted for detachable engagement with the other outer coil.

In testimony whereof, I affix my signature, in the presence of two witnesses.

HATTIE H. SELL.
